RAILWAY TRAFFIC CONTROLLING
APPARATUS

James J. Vanhorn, Pittsburgh, Pa., assignor to The
Union Switch & Signal Company, Swissvale,
Pa., a corporation of Pennsylvania

Application July 10, 1941, Serial No. 401,757

4 Claims. (Cl. 246—26)

My invention relates to railway traffic controlling apparatus, and more particularly to apparatus for control of track indicators.

The office of a remote control system for a railway is usually provided with a track model of the stretch of track associated with such control system, and track indicators in the form of small electric lamps are placed on such track model one for each of certain designated track sections of the stretch. Each such lamp is illuminated through the medium of the control system when the respective track section is occupied in order that the operator may know the location of the trains operating over the stretch. Wayside signals associated with track switches of passing sidings when governed by such remote control system are usually provided with approach locking which is controlled in part by approach relays, each of which relays is controlled by the track relay of one or more track sections in the approach to the respective signal. It is customary to use the approach relays as means for controlling track indicators, each such approach relay when deenergized in response to a train occupying the respective track section or sections, causing the remote control system to transmit an indication influence to the remote office where it results in a respective indication relay being energized and picked up to complete a circuit for the track model indicator lamp that corresponds to the same track section or sections. In this manner the operator is informed when a train is approaching a signal at which the operator can hold the train by setting the signal at stop or can advance the train by clearing the signal. When the remote control system is a centralized traffic control system of the time code type, the number of track occupied indication codes that can be provided without increasing the usual coding units and other apparatus is limited. In such centralized traffic control system for single track railroads it is desirable to provide track occupied indications for the track section or sections between adjacent passing sidings and for the track section or sections between the two ends of a siding.

In view of the above discussed circumstances in railway signaling systems, a feature of my invention is the provision of railway traffic controlling apparatus incorporating novel means for providing track occupied indications in centralized traffic control systems for railroads.

Another feature of my invention is the provision in centralized traffic control systems for single track railroads of novel means for indi-

cating at the office occupancy of the track stretch between the adjacent entering signals of adjacent sidings, and occupancy of the track stretch between the leaving signals at the two ends of a siding.

Again, a feature of my invention is the provision of novel and improved means for remote control systems for railways wherewith the occupancy of the stretch of track between adjacent sidings or between the two ends of a siding is indicated by the present equipment and additional repeater relays controlled over line circuits requiring line wires are avoided.

The above features of my invention, as well as other advantages which will become apparent from the following specification, are attained by controlling a track indicator corresponding to the stretch of track between adjacent passing sidings, or corresponding to the stretch of track between the two ends of a siding, over a circuit which includes in series a front contact of each of two indication relays, one governed by each of the two approach relays associated with signals of such stretch of track. In the case of a stretch between adjacent sidings, the approach relay of each of the two adjacent entering signals associated with such sidings is controlled over the track relay of each track section intermediate such entering signals as well as over the track relays of other sections in the approach to the respective signal. Each approach relay when deenergized due to a train approaching the respective signal causes an indication code to be transmitted to the office where a corresponding indication relay is energized and picked up. Since under such arrangement the only traffic condition under which the two approach relays of the two adjacent entering signals for adjacent sidings are deenergized at the same time is when the stretch of track between such signals is occupied, the indicator controlled over a circuit including a front contact of each of the two respective indication relays indicates a track occupied condition for this stretch of track only. I provide a directional stick relay for each approach relay for by-passing the control of the approach relay around the contact of the track relay of the usual detector track section for trains moving in the direction opposite to that governed by the associated signal. In the case of the stretch of track between the two ends of a siding, the track indicator is controlled over a circuit including in series a front contact of each of the two indication relays governed by the two approach relays of the two leaving signals of such siding. Again,

since the only condition in which the two approach relays are released at the same time is when a train occupies the stretch between the two leaving signals, such indicator is displayed only in response to occupancy of this stretch between the two ends of the siding.

I shall describe two forms of apparatus embodying my invention, and shall then point out the novel features thereof in claims.

In the accompanying drawings, Fig. 1 is a diagrammatic view showing one form of apparatus embodying my invention when used to indicate occupancy of a stretch of track between two adjacent sidings of a single track railway, and Fig. 2 is a diagrammatic view showing one form of apparatus embodying my invention when used to indicate occupancy of a stretch of track between the two ends of a passing siding of a single track railway. In each of the two views like reference characters are used to designate similar parts.

Referring to Fig. 1, the reference character F designates a stretch of single track railway which is provided with track switches 5S and 7S leading to sidings Fa and Fb. That is, track switches 5S and 7S are the adjacent switches of sidings Fa and Fb.

This stretch of track F is divided by the usual insulated rail joints into track sections 6T, 5T, A5T, 7T and 8T; the track sections 5T and 7T being detector track sections at switches 5S and 7S, respectively. Each such track sections is provided with a track circuit comprising a battery 2 connected across the rails at one end of the section, and a track relay designated by the reference character R plus a prefix corresponding to the associated section connected across the rails at the other end of the section.

Each track switch 5S and 7S is provided with the usual protecting signals, switch 5S being associated with entering signal L6 and leaving signals R6 and RC6, and switch 7S being associated with entering signal R8 and leaving signals L8 and LC8. These signals may be of any standard type and are shown by the usual conventional symbols, it being observed that entering signals L6 and R8 and leaving signals R6 and L8 comprise two signal mechanisms mounted on a single mast. Only certain of the control and operating circuits for these signals of Fig. 1 are shown for the sake of simplicity since such circuits form no part of my invention and all of them are not required for a full understanding of the invention. It is sufficient for this application to point out that these signals associated with the track switches are controlled in part by a centralized traffic control system to be described hereinafter and would also be controlled by traffic conditions of the stretch. It is to be noted that although the stretch of track between entering signals L6 and R8 is shown as consisting of but one track section A5T and no intermediate signals are provided it is to be understood that this portion of track may be formed into a plurality of track sections and intermediate signals may be located at selected points if desired. In the arrangement here shown, leaving signal LA8 serves as an approach signal for entering signal L6 and leaving signal RA6 serves as an approach signal for entering signal R8.

It should be pointed out at this time that in order to simplify the drawings, certain contacts of the several relays are shown remote from the relay winding and certain contacts of other devices are shown remote from the device. In each such instance the contact is identified by the

reference character for the relay or device being located adjacent thereto and by the contact being shown in the position corresponding to the normal position of the relay or device.

5 The signal R8 is provided with an approach control relay R8AR and the signal L6 if provided with an approach control relay L6AR. Approach control relay R8AR is included in a normal circuit which passes from terminal B of a suitable source of current such as a battery, not shown, over front contacts 10, 11 and 12 of track relays 6TR, 5TR and A5TR, respectively, winding of relay R8AR, front contacts 13, 14 and 15 of relays A5TR, 5TR and 6TR, respectively, and to terminal C of the same source of current. Thus approach relay R8AR associated with entering signal R8 at siding Fb is controlled by the track relay of detector track section 5T at the next adjacent passing siding Fa and by the track relay of section 6T in the approach to the leaving signal R6 at siding Fa as well as by the track relay of intermediate section A5T. In order to provide proper control of approach relay R8AR under the various traffic conditions at switch 5S, contacts 10 and 15 of track relay 6TR are by-passed by contacts 16 and 19, respectively, closed when signal RA6 is set at stop. Furthermore, front contacts 17 and 20 of a directional relay L6S to be referred to later, and front contacts 18 and 21 of a relay 5RWP also to be referred to later complete shunt paths for by-passing the circuit of approach relay R8AR around the control of track relays 5TR and 6TR as will be understood by an inspection of Fig. 1. It is to be seen therefore that approach relay R8AR is energized and picked up when track sections 6T, 5T and A5T in the approach to signal R8 are unoccupied; when sections 6T and A5T are unoccupied and section 5T is occupied if directional stick relay L6S is picked up closing front contacts 17 and 20; when sections 5T and A5T are unoccupied and section 6T is occupied providing signal L6 is set at stop closing contacts 16 and 19, and also when section A5T is unoccupied and relay 5RWP is picked up closing front contacts 18 and 21, irrespective of the traffic condition of sections 6T and 5T.

Approach relay L6AR is included in a normal circuit that passes from terminal B over front contacts 24, 25 and 26 of track relays 8TR, 7TR and A5TR, respectively, winding of relay L6AR, front contacts 27, 28 and 29 of relays A5TR, 7TR and 8TR, respectively, and to terminal C. Thus approach relay L6AR associated with entering signal L6 at siding Fa is controlled by the track relay of the detector track section 7T at the adjacent siding Fb and the relay of section 8T in the approach to the leaving signal L8 at siding Fb as well as by the track relay of intermediate section A5T. In order to provide proper control of approach relay L6AR for the different traffic conditions at switch 7S, front contacts 24 and 29 of track relay 8TR are by-passed by contacts 30 and 33, respectively, which are closed when signal LA8 is set at stop; front contacts 25 and 28 of track relay 7TR are by-passed by front contacts 31 and 34, respectively, of a directional stick relay R8S, to be shortly described; and contacts of both track relays 8TR and 7TR are by-passed by shunt paths including front contacts 32 and 35 of a relay 7RWP, also to be shortly described. Consequently, approach control relay L6AR is energized and picked up when sections 8T, 7T and A5T in the approach to signal L6 are unoccupied; when sections 8T and A5T are unoccupied and section 7T is occupied, providing directional re-

lay R8S is picked up closing front contacts 31 and 34; when sections A5T and 7T are unoccupied and section 8T is occupied providing signal LA8 is set at stop closing contacts 30 and 33; and when section A5T is unoccupied, and relay 7RWP is picked up closing front contacts 32 and 35.

From the foregoing description of the control of approach relays R8AR and L6AR it is to be observed that the only time these two relays are released at the same time is when section A5T is occupied. That is to say, the only time when these two approach control relays are both released is under the condition that the track section between the two entering signals L6 and R8 is occupied.

As stated hereinbefore, a centralized traffic control or remote control system is associated with the stretch of track F for controlling the switches 5S and 7S and the signals associated therewith. Such centralized traffic control system may take different forms and may be, for example, that covered by Letters Patent of the United States No. 2,229,249, granted January 21, 1941, to L. V. Lewis for Remote control systems. In the present application only that portion of the apparatus of such centralized traffic controlling system necessary for a complete understanding of my invention has been shown. An office FS is connected to stations 7-8 and 5-6 by a line circuit designated C. T. C. line circuit. Coding units which are indicated conventionally as CSO, CS7 and CS5 are provided at the office FS and stations 7-8 and 5-6, respectively. As set forth fully in the aforementioned Lewis Patent No. 2,229,249, the operator at the office FS can through the medium of the coding units transmit a control code to either station 5-6 or 7-8 for selectively energizing control relays which govern the positions of the track switch 5S or 7S as the case may be, or which govern the positions of the signals associated with these track switches. At station 5-6 only the control relays 5RWP and L6SR are shown since the other control relays located at this station are not involved in my present invention. Relay 5RWP when picked up is effective to cause operation of track switch 5S to its reverse position, that is, to the position for traffic to move to and from siding Fa, operation of the switch being accomplished by the usual power switch machine governed over a circuit controlled by relay 5RWP. The point to be noted in connection with relay 5RWP as far as the present application is concerned is the fact that front contacts 18 and 21 of that relay are included in the circuit network for approach relay R8AR, so that relay 5RWP when picked up to cause switch 5S to be set for movement to the siding, by-passes the control circuit of relay R8AR around track relays 5TR and 6TR and approach relay R8AR is released only at such time that track section A5T is occupied. It is to be noted that in place of using contacts 18 and 21 of switch control relay 5RWP for by-passing the circuit of approach control relay R8AR around track relays 5TR and 6TR, contacts 18 and 21 may be contacts of the usual switch repeater relay governed by the position of switch 5S.

Control relay L6SR at station 5-6 when picked up in response to a control code completes a circuit for a signal control relay L6AH, such circuit including terminal B, front contact 36 of relay L6SR, contact 39 operated by switch 5S and closed when the switch is set at its normal position, winding of relay L6AH, front contact 40 of track relay 5TR and terminal C. Relay L6AH

when picked up closing front contact 41 completes an obvious operating circuit for signal LA6 to operate that signal to a proceed position. In accordance with my invention relay L6AH also controls directional stick relay L6S, the pick-up circuit for relay L6S extending from terminal B over back contact 43 of track relay 5TR, front contact 42 of relay L6AH, winding of relay L6S and to terminal C. Relay L6S when picked up closing its own front contact 44 completes a stick circuit path around contact 42 of the signal control relay L6AH. It is to be recalled that front contacts 17 and 20 of relay L6S are interposed in the circuit network of approach relay R8AR. The function of directional stick relay L6S will appear when the operation of the apparatus of Fig. 1 is described.

At station 7-8 only the switch control relay 7RWP for governing operation of switch 7S to its reverse position, and the signal control relay R8SR for signal R8 are shown since the other control relays of this station are not involved in the present invention. Relay 7RWP when picked up in response to a proper control code transmitted from the office in addition to causing operation of switch 7S to its reverse position through the medium of the usual switch machine not shown, also controls at its front contacts 32 and 35 by-pass circuits in the circuit network for approach relay L6AR, as described hereinbefore. Again, it is to be noted that in place of using contacts 32 and 35 of switch control relay 7RWP to by-pass the circuit of approach relay L6AR around contacts of track relay 7TR and 8TR, contacts 32 and 35 may be contacts of the usual switch repeater relay governed by the position of switch 7S. Relay R8SR is picked up in response to a control code transmitted from the office and completes at its front contact 45 a circuit for a signal control relay R8AH, such circuit also including contact 46 closed when switch 7S is set at its normal position and front contact 47 of track relay 7TR. Signal control relay R8AH when picked up closing front contact 48, completes an obvious operating circuit for signal RA8 and this signal is operated to a proceed position. In accordance with my invention, signal control relay R8AH controls directional stick relay R8S, the pick-up circuit for relay R8S including terminal B, back contact 49 of track relay 7TR, front contact 50 of relay R8AH, winding of relay R8S and terminal C. Relay R8S when picked up to close its own front contact 51, completes a stick circuit path around front contact 50 of the relay R8AH. It is to be recalled that front contacts 31 and 34 of the directional stick relay R8S are interposed in the circuit network for the approach relay L6AR and the function of directional relay R8S will also appear when the operation of the apparatus of Fig. 1 is described.

At the office FS indication relays L6AK and R8AK and an indication lamp 5E have to do with the present invention. The lamp 5E is preferably on a track model of the stretch F to indicate when illuminated occupancy of track section A5T, that is, to indicate the presence of a train between the entering signals L6 and R8 of the adjacent sidings Fa and Fb. Indication relay L6AK is effectively energized and picked up by means of the centralized traffic control system in response to a preselected indication code transmitted from station 5-6, and which indication code is initiated when approach relay L6AR is released closing back contact 52 to apply positive voltage to a designated terminal of the coding

unit CS5 of station 5-6. Likewise, indication relay R8AK is effectively energized and picked up in response to a preselected indication code transmitted from station 7-8, and which indication code is initiated when approach relay R8AR is released closing back contact 53 to apply positive voltage to a designated terminal of the coding unit CS1 of station 7-8. Relays L6AK and R8AK when picked up complete a circuit for lamp 5E, such circuit including front contact 54 of relay L6AK in series with front contact 55 of relay R8AK as will be apparent by an inspection of Fig. 1.

In describing the operation of the apparatus of Fig. 1 it is to be noted that normally, that is, when the stretch of track F is unoccupied, the track relays are all picked up, and approach relays L6AR and R8AR are energized with the result that indication relays L6AK and R8AK at the office FS are released and lamp 5E is dark. In the event signal RA6 is operated to a proceed position to permit an eastbound train to move through the stretch of track F and such eastbound train enters section 6T, approach relay R8AR is released when track relay 6TR is shunted, and release of approach relay R8AR causes an indication code to be transmitted from station 7-8 which results in the indication relay R8AK at the office being energized and picked up. It is to be observed that approach relay R8AR in being released would also control the usual approach locking for signal R8. The eastbound train on advancing into detector section 5T shunts track relay 5TR to open additional points in the control circuit for approach relay R8AR. This eastbound train upon entering section A5T to shunt track relay A5TR opens the circuit for approach relay R8AR at additional points and also opens the circuit for approach relay L6AR associated with the westbound entering signal L6. The release of approach relay L6AR causes an indication code to be transmitted from station 5-5 which results in indication relay L6AK being picked up. Since both indication relays R8AK and L6AK are now energized and picked up, the lamp 5E is illuminated to indicate that the section A5T is occupied by this eastbound train. To advance this eastbound train beyond siding FB, the operator transmits a control code for picking up the relay R8SR at station 7-8 so that signal control relay R8AH is picked up and the signal RA8 is operated to a proceed position. The eastbound train upon moving past signal R8 to enter section 7T shunts track relay 7TR causing signal control relay R8AH to be deenergized and released and signal RA8 to be restored to its stop position. Signal control relay R8AH is slow releasing in character and hence when track relay 7TR is shunted closing its back contact 49 the pick-up circuit of directional stick relay R8S is closed during the slow release period of relay R8AH, and relay R8S when thus picked up is retained picked up subsequent to the release of relay R8AH over its stick circuit with the result that directional relay R8S remains picked up until such time as the eastbound train vacates track section 7T and track relay 7TR is picked up. Since for eastbound traffic, the westbound signal LA8 is set at stop closing contacts 30 and 33 and since directional stick relay R8S is picked up closing front contacts 31 and 34, the circuit network for approach relay L6AR is closed around the control of track relays 7TR and 8TR with the result that approach relay L6AR is re-energized and picked up as soon as the train

vacates track section A5T. The approach relay R8AR is also picked up when the train vacates track section A5T unless a second or following eastbound train happens to be occupying the section 6T or the section 5T. It is to be seen therefore that under normal movement of eastbound traffic both approach relays R8AR and L6AR are reenergized when the eastbound train vacates section A5T and both indication relays R8AK and L6AK are released causing lamp 5E to become dark. Furthermore, in the event a second eastbound train occupies section 6T causing approach relay R8AR to remain released and its corresponding indication relay R8AK to remain energized, subsequent to the first eastbound train vacating section A5T, the other approach relay L6AR is reenergized and picked up causing indication relay L6AK to be deenergized with the result that lamp 5E becomes dark indicating that the track section A5T between the two sidings is unoccupied. In other words, indication lamp 5E when illuminated informs the operator that the track between the entering signals R8 and L6 is occupied.

The operation of the apparatus of Fig. 1 for a westbound train is similar to that just described in connection with an eastbound train, and it is believed that the operation of the apparatus for westbound traffic will be apparent from an inspection of Fig. 1 when considered in connection with the description of the operation of the apparatus for eastbound traffic.

It should be pointed out that the released position of directional relay R8S associated with eastbound traffic is checked by the fact that its back contact 56 is interposed in the control of the westbound signals LA8 and LC8, and that the released position of directional relay L6S associated with westbound traffic is checked by its back contact 57 being interposed in the control of eastbound signals RA6 and RC6.

Referring to Fig. 2, a stretch of single track F1 includes both ends of passing siding Fa, such siding being provided with track switches 5S and 3S. This stretch F1 is formed into track sections A2T, 3T, 4T, A4T, 6T, 5T and A5T; and each of which track sections is provided with a track circuit including a battery 2 connected across the rails at one end of the section and a track relay R plus a prefix corresponding to the section connected across the rails at the other end of the section. Traffic at switch 5S is governed by entering signal L6 and leaving signals R6 and RC6, and at switch 3S by entering signal R4 and leaving signals L4 and LC4. It is to be noted that there are three track sections 4T, A4T and 6T between leaving signals R6 and L4. These signals of Fig. 2, like the signals of Fig. 1, would be controlled in part by traffic conditions of the associated stretch and in part by a centralized traffic control system. Of such control for the signals of Fig. 2, only that portion that has to do with the present application is shown. In Fig. 2 an approach relay R6AR associated with signal R6 is normally energized by a circuit formed from terminal B over front contacts 58, 59, 60, 61 and 62 of track relays A2TR, 3TR, 4TR, A4TR and 6TR, respectively, winding of relay R6AR, front contacts 63, 64, 65, 66 and 67 of track relays 6TR, A4TR, 4TR, 3TR and A2TR, respectively, and to terminal C. In the circuit for approach relay R6AR contacts 68 and 69 closed when signal R4 is set at stop, by-pass front contacts 58 and 67, respectively, of track relay A2TR, and the front contacts 70 and 71

of a switch control relay 3RWP to be referred to later, form a shunt path around the contacts of both track relays A2TR and 3TR.

An approach control relay L4AR for signal LA4 is provided with a normal circuit including terminal B, front contacts 12, 13, 74, 75 and 76 of relays A5TR, 5TR, 6TR, A4TR and 4TR, respectively, winding of relay L4AR, front contacts 77, 78, 79, 80 and 81 of relays 4TR, A4TR, 6TR, 5TR and A5TR, respectively, and terminal C. In this circuit two contacts 82 and 83 closed when signal L6 is set at stop by-pass front contacts 72 and 81 of relay A5TR and contacts 84 and 85 of switch control relay 5RWP form shunt paths around the contacts of both track relays 5TR and A5TR.

In the associated centralized traffic control system, the office FS is connected to stations 5—6 and 3—4 over the C. T. C. line circuit, and coding units CSO, CS5 and CS3 of office FS and stations 5—6 and 3—4, respectively, are associated with such line circuit in the same manner as explained in connection with Fig. 1 and as fully explained in Patent No. 2,229,249, referred to hereinbefore. At station 5—6, only the one control relay 5RWP is shown since that is the only control relay involved in the apparatus of Fig. 2 and this relay is effectively energized and picked up in response to a control code transmitted from the office and relay 5RWP when picked up is effective to set in motion the operation of moving switch 5S to its reverse position the same as in Fig. 1. The point to be noted in connection with control relay 5RWP in Fig. 2 is the fact that when this relay is picked up closing front contacts 84 and 85, by-pass paths are formed for the circuit of approach relay L4AR around the contacts of track relays 5TR and A5TR. At stations 3—4, only the one control relay 3RWP is shown since this is the only control relay at that station involved in the present application. Relay 3RWP is picked up in response to a proper control code transmitted from the office and when picked up it is effective to cause operation of switch 3S to its reverse position and to complete at its front contacts 70 and 71 by-pass paths around the contacts of track relays 3TR and A2TR for the circuit of approach control relay R6AR. It should again be pointed out that in place of contacts of the switch control relays 3RWP and 5RWP being used in the networks of the associated approach relays, contacts of the usual switch repeater relays governed by the positions of switches 3S and 5S can be used in the networks since a switch repeater relay indirectly repeats the position of the switch control relay.

At the office an indication relay L4AK is energized in response to an indication code sent out from station 3—4 due to approach relay L4AR being released to close back contact 86 and applying positive voltage to a designated terminal of the coding unit CS3. Indication relay R6AK at the office is energized in response to an indication code sent from station 5—6 when approach relay R6AR is released to close back contact 87 and apply positive voltage to a designated terminal of coding unit CS5. Indication relays L4AK and R6AK when picked up to close front contacts 88 and 89, complete a simple circuit for indication lamp 4E which is preferably located in the track model of the stretch of track F1.

In describing the operation of the apparatus of Fig. 2, it is to be observed that normally, that is, when the track sections are all unoccupied,

the track relays are all picked up and approach relays R6AR and L4AR are energized with the result that the indication relays L4AK and R6AK are released and the track indicator lamp 4E is dark. In the event an eastbound train is to move through the stretch F1 and enters the track section A2T in approach to signal R4 as well as in the approach to signal R6, the approach relay R6AR is deenergized and released, if signal RA4 is operated to a proceed position for an eastbound train, closing back contact 87 and causing an indication code to be transmitted which results in the indication relay R6AK being energized. When the train passes signal RA4 and enters track section 3T, track relay 3TR is shunted to open the control circuit for approach relay R6AR at additional points and when the eastbound train enters section 4T to shunt track relay 4TR, the circuit for approach relay R6AR is opened at other additional points and the circuit for the approach relay L4AR is opened. Relay L4AR when released to close back contact 86 causes an indication code to be transmitted from station 3—4 which results in indication relay L4AK being energized. Both indication relays L4AK and R6AK at the office being now picked up, the lamp 4E is illuminated to inform the operator that the section 4T is occupied by the eastbound train. This condition is continued while the eastbound train traverses the track sections A4T and 6T, since track relays A4TR and 6TR both control the circuits for both approach relays R6AR and L4AR. In other words the indication lamp 4E is continuously illuminated while the eastbound train occupies the track sections between leaving signals L4 and R6.

Assuming that signal RA6 is operated to a proceed position to permit this eastbound train to enter section 5T, the control circuit for approach relay L4AR is held open at front contacts 73 and 80 of track relay 5TR while approach relay R6AR is reenergized and picked up when the train vacates the section 6T and approach relay R6AR on being picked up causes indication relay R6AK to be deenergized with the result that lamp 4E becomes dark to indicate that the train has vacated the stretch between the signals L4 and R6.

In the event it is desirable to reenergize approach relay L4AR when this eastbound train occupies detector section 5T, a directional stick relay similar to relay R8S of Fig. 1 would be provided at field station 5—6 of Fig. 2 and controlled over circuits governed by the control relay for signal R6 in the same manner that relay R8S of Fig. 1 is controlled by the signal control relay for signal R8.

The operation of the apparatus of Fig. 2 for a westbound train is similar to that just described for an eastbound train and a description of the operation for a westbound train is believed not to be necessary and will be apparent from an inspection of Fig. 2 when considered in connection with the description of the operation of the apparatus for an eastbound train.

It is to be seen therefore that I have provided novel and improved means for indicating occupancy of a center portion between the two end portions of a stretch of track, such as, for example, the intermediate track section between the two detector track sections of adjacent passing sidings, or the intermediate track section between the two detector track sections at the two ends of a passing siding, and repeater relays for the track sections of such stretches governed

over line circuits requiring additional line wires are not required.

Although I have herein shown and described only two forms of railway traffic controlling apparatus embodying my invention, it is understood that various changes and modifications may be made therein within the scope of the appended claims without departing from the spirit and scope of my invention.

Having thus described my invention, what I claim is:

1. In combination, a stretch of single track railway including the adjacent track switches of two adjacent sidings, said stretch arranged with a detector track section at each of said switches and an intermediate track section between such detector sections, an entering signal for each siding located at the junction of the detector section of that siding and the intermediate section, a track circuit including a track relay for each of said sections, an approach relay for each of said signals controlled over a circuit including a front contact of the track relay of the intermediate section and a front contact of the track relay for the detector section remote from the respective signal, a remote control system associated with said stretch and including two signal control relays one for each of said signals, a directional relay for each detector section and effective when energized to by-pass the respective approach relay circuit around the track relay of the respective detector section, means governed by each signal control relay when picked up to energize the directional relay for the detector section at which the associated signal is located, two indication relays one for each approach relay and each such indication relay energized by said remote control system when the respective approach relay is released, and a track indicator controlled over a circuit including in series a front contact of each of said indication relays to indicate when a train occupies said intermediate section only.

2. In combination, a stretch of single track railway including two adjacent sidings and arranged with an intermediate track section between the two detector track sections for the adjacent switches of the sidings, a track circuit including a track relay for each of said track sections, two entering signals one for each siding, an approach relay for each such signals, a control circuit for each approach relay and including a contact of the track relay for the detector section at the switch remote from the respective signal and a contact of the track relay of the intermediate section, a remote control system associated with said stretch and including two signal control relays one for each of said signals, two directional relays one associated with each said signal control relay and energized over a pick-up circuit including a front contact of the respective signal control relay and a back contact of the track relay for the detector section adjacent the signal governed by that signal control relay, a by-pass circuit for each of the approach relay control circuits to by-pass the circuit around the front contact of the respective detector section track relay and including a front

contact of the directional relay for the signal control relay of the signal governing traffic over that detector section, two indication relays one for each of said approach relays and each said indication relay energized by said remote control system when the respective approach relay is released, and a track indicator controlled over a circuit including in series a front contact of each of said indication relays.

3. In combination, a stretch of single track formed with two spaced detector track sections each of which includes a track switch and which sections are separated by at least one intermediate track section, a track circuit including a track relay for each of said sections, a signal at each detector circuit to govern traffic over the respective track switch away from said intermediate section, an approach relay for each of said signals controlled through a circuit including a front contact of the track relay of each intermediate section and a front contact of the track relay of the detector section remote from the respective signal, a remote control system having an office from which said signals and switches are governed, means governed by said remote control system to by-pass each approach relay circuit around the front contact of the respective detector section track relay according to the control established for the switch and signals associated with that detector section, two indication relays at said office one for each of said approach relays, means governed by each approach relay to energize the respective indication relay through said remote control system when the respective approach relay is released, and a track indicator controlled by a circuit including in series a front contact of each of said indication relays.

4. In combination, a stretch of single track railway including a passing siding, a leaving signal at each end of said siding, said stretch formed with a detector track section at each switch of the siding and at least one intermediate track section between said detector sections, a track circuit including a track relay for each of said sections, an approach relay for each of said signals, each of said approach relays controlled by a circuit including a front contact of the track relay for said intermediate section and a front contact of the track relay for the detector section remote from the respective signal, a remote control system including a remote office for said stretch for governing the switches and signals associated with said siding and said system provided with a switch control relay for each said switch, means governed by each of said switch control relays to at times by-pass the approach relay circuit around the front contact of the detector track circuit at the respective switch, two indication relays at said office one for each of said approach relays, means governed by each of said approach relays to energize the respective indication relay through said remote control system, and an office track indicator controlled by a circuit including in series a front contact of each of said indication relays.

JAMES J. VANHORN.
